Attorneys.

UNITED STATES PATENT OFFICE.

HERBERT GARDNER, OF COLORADO SPRINGS, COLORADO.

DESIGN FOR A GAME-BOARD.

SPECIFICATION forming part of Design No. 23,036, dated February 6, 1894.

Application filed December 7, 1893. Serial No. 493,046. Term of patent 3½ years.

To all whom it may concern:

Be it known that I, HERRERT GARDNER, a citizen of the United States, residing at Colorado Springs, in the county of El Paso and State of Colorado, have invented certain new and useful Improvements in Designs for Game-Boards; and I do declare the following to be a full, clear, and exact description of the invention, such as will enable others skilled in the art to which it appertains to make and use the same, reference being had to the accompanying drawing, and to the letters of reference marked theron, which forms a part of this specification.

15 In the accompanying drawing which illustrates a perspective view of a game board having my design applied, the letter *a*, indicates a rigid standard mounted upon a base portion *b*, and arising vertically therefrom. This

20 standard is annular in cross-section and the standard is shaped so as to appear of gradual thickness, and with each different thickness terminating at its upper extremity in an abrupt shoulder *c*. Mounted upon the shoulder

25 *c* are the circular disks *d*, which are of different sizes, the largest disk being arranged di-

rectly upon the base *b*, while the smallest is arranged at the highest extremity of the standard *a*, the intermediate disks being gradually reduced as they ascend, so as to give 30 a regular appearance to the game board and so as to conform to the arrangement of the upper and lower disks. The peripheries of these disks *d*, are formed with a vertically extending flange *e*, which operates to give 35 the disks a pan-shaped appearance. The top disk is mounted upon the highest extremity of the standard *a*, and is secured thereon by an ornamental washer or screw *f*.

Having thus pointed out the distinguishing 40 features of my design and shown wherein they affect its appearance, what I claim, and desire to secure by Letters Patent, is—

The design for a game board substantially as herein described and shown.

In testimony whereof I affix my signature in presence of two witnesses.

HERBERT GARDNER.
